US0D1091048S

(12) **United States Design Patent** (10) **Patent No.:** **US D1,091,048 S**
(45) **Date of Patent:** **** Aug. 26, 2025**

(54) **RIGGING DEVICE**

(71) Applicants: **Patrick Daniel Pollin**, Ashaway, RI (US); **Timothy Thomas Tylaska**, Preston, CT (US)

(72) Inventors: **Patrick Daniel Pollin**, Ashaway, RI (US); **Timothy Thomas Tylaska**, Preston, CT (US)

(**) Term: **15 Years**

(21) Appl. No.: **29/863,127**

(22) Filed: **Dec. 15, 2022**

(51) **LOC (15) Cl.** **09-06**

(52) **U.S. Cl.**

USPC **D8/356; D34/35**

CLAIM

The ornamental design for a rigging device as shown.

DESCRIPTION

FIG. 1 is a top axonometric view of the rigging device showing our new design.

FIG. 2 is a bottom axonometric view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

1 Claim, 6 Drawing Sheets
